Specification for Design.

Patented Aug. 27, 1918.

Application filed May 23, 1917. Serial No. 170,558. Term of patent 3½ years.

To all whom it may concern:

Be it known that I, GEORGE K. CULP, a citizen of the United States, residing at Kansas City, county of Jackson, and State of Missouri, have invented a new, original, and ornamental Design for Articles of Manufacture, of which the following is a specification, reference being had to the accompanying drawing, forming part thereof, in which—

Figure 1 is a side elevation of a section of tire showing my design, and

Fig. 2 is a plan view of the same.

I claim:

The ornamental design for an article of manufacture, as shown.

Signed at Kansas City, Mo., this 10th day of May, 1917.

GEORGE K. CULP.
